(57) **CLAIM**

The ornamental design for a storage case, as shown and described.

DESCRIPTION

FIG. 1 is a perspective view of a storage case showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is an exploded front elevational view thereof; and,
 FIG. 8 is an exploded left side elevational view thereof.

The broken lines in the drawings depict portions of the storage case that form no part of the claimed design.
